UNITED STATES PATENT OFFICE

2,584,260

QUOIT

Carl M. Custer, Cincinnati, Ohio

Application June 5, 1948; Serial No. 31,260

2 Claims. (Cl. 273—106)

1

This invention relates to game devices and more particularly relates to a quoit-like device for use in a game of the type in which the device may be pitched, thrown, or slid against a post or stake or in other games.

An object of this invention is to provide a quoit-like device which can be thrown against a post to encompass the post.

A further object of this invention is to provide a device of this type having angularly spaced openings about its periphery for encompassing the post.

A further object of this invention is to provide a device of this type which is symmetrical and which presents horse-shoe like openings on all sides.

A further object of this invention is to provide a device of this type which, when thrown with a rotary motion, may engage the post on any side.

A further object of this invention is to provide a device of this type which may have top and bottom sides which are identical in appearance and design.

The above and other objects may be attained by the means described herein and illustrated in the accompanying drawings, in which:

Figure 1 is a plan view of a quoit-like game device constructed in accordance with this invention.

Figure 2 is a side elevational view of the device illustrated in Figure 1.

Figure 3 is a perspective view of an arm of the device illustrated in Figure 1.

Briefly, the device may include a central supporting body portion and a plurality of outwardly extending arms, all of the arms being in a single plane. Each of the arms may be bent in substantially an arc of a circle to form a flat device having a plurality of substantially horse-shoe shaped openings about the central body portion. Each opening may be between a concave side of an arm and a convex side of an adjacent arm. A free end of each of the arms may be provided with an inwardly directed tooth for engaging the post for holding the device about the post. The arms may be provided with scoring indicia indicating a point value to be associated with each arm.

Referring now to the drawing, the device may include a central portion 10. The central portion 10 may be flat and triangular in shape and may have parallel outer sides 12. Outwardly projecting arms 13, 14, and 16 may be integral with and may extend outwardly from the central por-

2

tion 10. The central portion 10 may be gripped by a player for holding the device while pitching or throwing it, or one of the arms 13, 14, and 16 may be gripped.

5 Each of the arms 13, 14, and 16 may project radially from the central portion 10, and the arms may all be of the same shape. As shown in Figure 3, each arm may be of substantially rectangular cross-section and may curve throughout its length. The edges of each arm may be cut away or beveled as indicated at 17 to eliminate sharp edges, and each arm may be provided with lengthwise strengthening ribs or the like if desired.

10 The free end of each arm may be enlarged as indicated at 18, and a portion of the enlarged end 18 may project inwardly to form a tooth 19 for holding the device on a post (not shown) when the device is pitched against the post. In addition, the enlarged end portion 18 may include lips 24 which extend upwardly and downwardly from each arm to engage dirt or sand about the post.

15 As shown in Figures 1 and 2, the device may be symmetrical so that it will fly true when pitched or thrown with a rotary motion. The top and bottom sides, as shown, may be identical, and the device may be thrown with either side up. All the arms may project from the central portion 10 in a single plane, and the device may lie flat on the ground or may slide over the ground parallel with the ground when it hits the ground.

20 The device shown is equipped with three arms, but, as will be apparent, similar devices may be constructed with more than three arms for presenting additional openings which can engage the post.

If desired, each of the arms may be equipped 25 with scoring indicia 22 to provide a variety of scoring values for ringers or arms encompassing the post, and the arms may be of various colors for ease in identifying.

When the device is to be used, it may be 30 grasped at the central portion 10 or may be held by one of the arms, and the device may be pitched or thrown toward the post like a horse-shoe but with the radiating arms revolving toward the post at which the device is thrown.

35 When the device hits the post, it may encompass the post, and the post may fit between an inner curved or concave side 23 of an arm and an outer curved or convex side 24 of an adjacent arm. As shown in Figure 2, the concave side 23 of one arm may be continuous with and

may merge into the convex side 24 of the adjacent arm. The teeth 19 serve to retain the device about the post, and the lips 21 and the side 12 on the lower side of the device may engage dirt about the post to limit the distance which the device can slide along the ground. As shown, the lips 21 may be symmetrically arranged about the central portion 10. The outer sides 12 of the central portion 10 and outer sides of the lips 21 may be in the same planes, and there may be less tendency for the device to roll after hitting the ground than there is with a horseshoe, which is not symmetrical.

Alternately, the device may be slid along a smooth surface, such as a floor, as in shuffleboard, to engage a post. As another alternative, the device may be used in a game similar to deck tennis, and the arms can provide projections for ready catching by players.

Scoring may be in any desired manner. If desired, the indicia 22 may be used and, for example, five points may be scored when the arm 16 encompasses the post, three points may be scored when the arm 14 encompasses the post, and one point may be scored when the arm 13 encompasses the post. When employed in a game similar to deck tennis, a penalty may be invoked when a selected arm is caught.

The device may be constructed of any appropriate durable material such as a wrought iron, rubber, a plastic material, or the like or combinations of these materials. If desired, the arms may consist of cores of hard material, such as iron, coated with a soft material such as rubber or a plastic material. The arms of the device illustrated have a circular curvature, and each arm may curve approximately 90 degrees between the central portion 10 and the enlarged end portion 18, while the concave side 23 of each arm may curve approximately 180 degrees to form a semi-circular opening for receiving the post. However, arms of differing curvatures or arms having angular displacement may be substituted for the circularly curved arms shown.

The device may be made from a single piece of material cast, forged, machined, molded or otherwise shaped, and the arms 13, 14, and 16 may be integral with the central portion 10 and with the enlarged end portions 18. As shown in Figures 2 and 3, each end portion may terminate in a surface 26 which may receive and absorb a blow if the end portion 18 hits the post. A side of the surface 26 adjacent the convex side 24 of the arm may be cut away as at 27 for eliminating sharp corners. Each tooth 19 may have substantial thickness between the surface 26 and an inner curved surface 28 which may merge with the concave side 23 of the arm.

As shown in Figures 1 and 2, corners of the triangular central portion 10 may be cut away at the points to form platforms 29, which do not extend outwardly as far as the sides of the central portion 10. The scoring indicia 22 may be located on the platforms 29 where the indicia 22 are protected by the outwardly extending sides of the central portion 10.

As shown in Figure 1, the points of the triangular central portion 10 are directed along the arms. Flat sides 31 of the central portion 10

face outwardly toward the ends 18 of the arms, and the sides 31, being directed toward the ends 18 and toward the openings, can act to brake the sliding of the device over the ground as it approaches the post. The central portion 10 has been shown of triangular shape, but may be of other shapes. If the device is provided with more than three arms, the central portion may have a side for each arm, or the central portion may have other shapes, for example a star shape or a circular shape.

Many other variations in details of construction of the device will be apparent, and the invention is not intended to be limited by the foregoing detailed description and by the drawing except as set out in the appending claims.

What I claim is:

1. A game device for pitching against a post which comprises, a central body portion, a plurality of arms projecting radially from and arranged symmetrically about said central body portion in a single plane, each of said arms being curved to define openings about the periphery of the device, each opening being between a concave side of an arm and convex side of an adjacent arm, the concave side of each arm merging into and forming an extension of the convex side of the adjacent arm, and inwardly projecting teeth at free ends of the arms for engaging the post.

2. A one piece game device for pitching against a post which comprises, a central body portion, three arms projecting radially from said central body portion in a single plane, each of said arms being curved in an arc of a circle to define openings about the periphery of the device, each opening being between a concave side of an arm and a convex side of an adjacent arm, the concave side of each arm merging with the convex side of the adjacent arm, inwardly projecting teeth at free ends of the arms for engaging the post, lips, a pair of lips for each arm, projecting in opposite directions from the free ends of the arms substantially perpendicularly to the plane of the arms for engaging the ground, and a pair of triangular shaped projections, one on each side of the central body portion for engaging the ground, said arms, teeth and lips being arranged symmetrically about the central body portion, outer surfaces of the projection and lips on each side of said device being coplanar, each side of each triangular shaped projection facing the free end of one of said arms.
